UNITED STATES PATENT OFFICE.

SAMUEL B. WILLIAMS, JR., OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed June 20, 1921. Serial No. 478,816.

To all whom it may concern:

Be it known that I, SAMUEL B. WILLIAMS, Jr., a citizen of the United States, residing at Brooklyn, in the county of Kings, State of New York, have invented certain new and useful Improvements in Telephone-Exchange Systems, of which the following is a full, clear, concise, and exact description.

- 10 This invention relates to telephone exchange systems and more particularly to systems of the character wherein machine switching devices are employed for the extension of talking connections.
- 15 In telephone systems where the extension of certain classes of connections involve a plurality of separate offices, the connections in any two adjacent offices being built up either entirely or in part by means of automatic switches, it is in some cases desirable to have the switches in each of the offices concerned governed by separate controlling mechanisms correspondingly located in the offices containing the switches which they
- 20 control. In other words, the selective switches in the first office involved, for example, in the extension of a connection including only two offices, are positioned under the control of mechanism thereat to extend the connection over an interoffice trunk line to the distant office. In the distant office the selective switches, which participate in the further establishment of the connection, are governed by a separate controlling mechanism located in the distant office. The
- 25 expedience of this method of separate control, instead of arranging to have the switches in all offices governed from a single controlling mechanism, arises particularly in interoffice systems where different offices are equipped with selective switching apparatus of widely differing character.
- 30 One instance of this condition is an inter-office system in which connections are established from an office provided with switches of the step-by-step type over an interoffice trunk to a distant office equipped with switches of the revertive control power driven type. In the distant office the power
- 35 driven switches are operated under the con-

trol of a register sender thereat which receives its record over the connection extended from the calling office.

Due to the fact that the impulses, which cause the setting of the register sender at the distant office in accordance with a portion of the complete designation, are transmitted from a subscriber's or operator's dial, and follow in rapid succession the impulses which govern the setting of the step-by-step selectors in the calling office, it is imperative that a register sender be attached to the incoming trunk immediately that such trunk is seized by the last switch in the calling office. Otherwise, part of the impulses intended to be recorded on the sender may be lost or mutilated. Furthermore, due to the importance of having a sender available to serve a calling trunk, it is desirable that all senders provided to handle this class of connections may be arranged for universal use and appropriated by all trunks regardless of the fact that a grouping relation normally exists between trunks and senders.

Accordingly, it is one of the objects of the present invention to provide a system of the foregoing character wherein a plurality of register senders are each respectively associated with a plurality of groups of trunks, and normally arranged to serve the trunks of the group to which they are individual, together with means for enabling any one of said senders to serve the trunks of groups other than the group to which it is normally individual.

A feature of the invention relates to the provision of a plurality of groups of senders, one normally individual to and adapted to serve each group of trunks, and means whereby when all senders of the group, normally serving a particular group of trunks, are busy, a sender of some other group may be rendered effective to serve the trunks of such particular group.

A further feature relates to the provision of means whereby the register senders, which normally serve the trunks of their respective individual groups of trunks and, under certain conditions, the trunks of other groups are immediately connected to such

trunks through the contacts of connecting relays.

Such other and further features as are contemplated in the present invention will 5 become more clearly understood from the following description and from the appended claims.

In the drawing, Figs. 1 to 9 inclusive, when 10 taken in the order illustrated in Fig. 10, disclose the details of a telephone exchange 15 system embodying the principles covered in this application.

Fig. 1 shows one of a plurality of subscribers' lines terminating in an individual 20 switch at the central office, diagrammatically illustrated. This figure also illustrates, in diagrammatic manner, a group selector switch of the step-by-step type and the detailed circuits of a repeater located in the same office.

Fig. 2 shows one of a group of interoffice 25 trunk circuits incoming from the repeater at the distant office and terminating in an incoming selector switch of the power driven type located in the distant office. There is also disclosed in this figure a diagrammatic 30 illustration of a final selector switch, which, in cooperation with the incoming switches, establishes connections through to the called subscribers' lines.

In the rectangular space, set off by broken 35 lines in the upper part of Fig. 3, is shown a second trunk terminating in an incoming selector switch belonging to the same group as the trunk shown in Fig. 2, together with 40 certain relays and circuits individual to this trunk. This figure further illustrates four pairs of multi-contact connecting relays, each pair individual to a group of incoming trunk circuits and the function of which is to connect the senders to a trunk of the group to which such relays are individual.

In the space set off by broken lines in the 45 upper part of Fig. 4 there is diagrammatically shown one of the trunks of the second group of trunks incoming to the distant office and terminating in an incoming switch. Below the broken lines this figure illustrates 50 four pairs of multi-contact connecting relays associated with the second group of trunks, each pair corresponding to a pair of relays shown in Fig. 3 and serving a similar purpose.

In the space set off by broken lines in the 55 upper part of Fig. 5, one of the trunks of the third group of inter-office incoming trunks is illustrated, together with certain relays and operating circuits therefor. The remainder of the figure shows four pairs 60 of connecting relays associated with this third group of trunks and having the same function as the relays shown in Figs. 3 and 4.

Fig. 6 shows a controlling and selecting

circuit associated with the first group of 65 incoming trunks, of which two are illustrated in Figs. 2 and 3, the purpose of which is to connect the register senders to any of the trunks in this group.

Figs. 7 and 8 show controlling and selecting 70 circuits similar to Fig. 6 and individual respectively to the second and third groups of incoming trunks.

Fig. 9 illustrates, in diagrammatic manner, two register senders of the group which 75 normally serves the trunks of the first group of trunks, namely that group containing the two trunks shown in Figs. 2 and 3.

The system herein disclosed is one in which the extension of a connection from a 80 calling line to a called line takes place over selective switches of the step-by-step type in a first office, an inter-office trunk to a distant office and thence over switches of the power driven character located in the distant 85 office. The calling subscriber's line is shown terminating in the brushes 102, 103, 104 of an individual switch having access to the terminals 105, 106, 107 of trunks leading to first selector switches. These individual 90 switches may be of any well-known and approved type. The first selector switch, illustrated by the brushes 108, 109, 110, is of the well-known step-by-step character arranged to be selectively operated by impulses 95 transmitted from the subscriber's dial and has access to the terminals 111, 112, 113 of trunks which lead to the distant office. In the outgoing end of each of these trunks a repeating mechanism is provided which receives a series of impulses from the calling 100 subscriber's dial and repeats them over the conductors 121, 122 of the inter-office trunk to cause the positioning of the registers of the register sender at the distant office in 105 accordance with that portion of the called designation which determines the setting of the incoming and final selector switches 224 and 225 to select the called subscriber's line.

At the distant office the incoming selector 110 switches, designated generally by the characters 224, 300, 400 and 500 and the final selector switches, one of which is indicated at 225, are of the revertive impulse control power driven type and may be of the same 115 construction and operation as the one shown in the patent to Craft and Reynolds, No. 1,123,696, issued January 5, 1915.

The sequence switch 210, which controls the changing operation of the circuits of the 120 incoming selector switch 224, is of the same construction and principle as the one described in patent to Reynolds and Baldwin, No. 1,127,808, issued February 9, 1915. The same is true of the sequence switches 910 125 and 920 belonging to the register senders shown in Fig. 9.

The register senders, illustrated only in

part herein, consist of a plurality of registers for recording the designation of called lines, impulse receiving mechanism for positioning these registers, counting relays for controlling the setting of the selective switches in accordance with the designations recorded and the other usual elements. These senders may be of the same general type as the one shown and described in the 10 patent to Stearn and Scudder, No. 1,395,977, issued November 1, 1921.

The incoming trunks 121, 122 from the calling step-by-step office are divided at the distant office into a plurality of groups. In 15 order to facilitate an explanation of the manner of division, it will be assumed that each major group of 120 incoming trunks is subdivided into twelve groups of ten trunks per group. To each of these twelve 20 groups of trunks a group of register senders is assigned to control the connection incoming on such trunks. The number of senders assigned to serve a group of ten trunks will, of course, be determined by the nature 25 of the traffic. In the present disclosure only two senders have been illustrated as serving each of the several groups. The first group of ten trunks containing the trunks 121, 122 and 301,302 is accommodated by the 30 group of two senders 900 and 915 shown in Fig. 9. These senders normally serve all connections incoming over the trunks of the group to which they are individual and may be taken for use and associated with 35 any calling trunk in the group. If both senders are idle when a call appears on one of the group of ten trunks, the first sender 900 is connected to that trunk, but if this sender happens to be busy at the time then 40 the next sender 915 is taken.

The second group of senders, not shown herein, is assigned to normally serve the trunks of the second incoming group, of 45 which trunk 401, 402 is one. Certain sequence switch contacts 740, 741, belonging respectively to the two senders of the second group, are shown within the area set off by broken lines at the bottom of Fig. 7. In like manner the two senders of the second group are, when idle, utilized normally 50 for the purpose of controlling connections extended over the trunks of the second group.

Similarly, a group of two senders will be 55 provided for normally serving the calls on incoming trunks of the third group, one of which trunks is shown in Fig. 5. For each of the remaining nine groups of trunks a corresponding group of register senders 60 is provided for normally serving calls incoming thereon.

The register senders are arranged to be connected to the trunks by means of multi-contact connecting relays. The coordinate

principle of selection is employed, there being a group relay for each group of trunks and a units relay for each of the trunks in the group normally served by said senders. For example, the relay 304 is individual to the first group of trunks and 65 connects these trunks with the first sender 900 of the group of senders. Relays 606, 607, 608 are individual to the first three trunks respectively of the group of ten. There will, of course, be a units relay for 70 each of the remaining trunks. The group relay 304 is provided with a set of contacts for each of the ten trunks of the group, whereby, when this relay is energized, the three controlling conductors individual to 75 each trunk are extended through the armatures and contacts of such relay. At the same time the particular units relay, individual to the trunk with which it is desired to associate the sender 900, is energized, whereby the three controlling conductors, such as conductors 227, 228 and 229, are further extended over the armatures and contacts of said relay to the register 80 sender 900. The multi-contact group 85 relay 305 is also individual to the first group of ten trunks and operates to associate the second sender 915 of the first group of senders with these trunks. It operates to extend the controlling conductors of all ten trunks 90 through to the contacts of the ten units relays individual to the second sender of which three are shown, namely relays 613, 614 and 615. The relays 613, 614 and 615 are, like relays 606, 607 and 608, respectively 100 individual to the several trunks of the group. Consequently, the energization of relay 305 and the energization of the particular one of the ten units relays individual to the calling trunk serves to extend the 105 three controlling conductors to the second register sender 915. Should other register senders be provided for each group there would also be a group relay similar to relays 304 and 305 for each additional sender, together with a set of individual units relays 110 similar to relays 613, 614 and 615.

The selection of the group relays 304, 305, etc., is initiated by the presence of the calling condition of one of the incoming trunks of the group with which these relays are associated and depends upon the busy or idle condition of the register senders normally serving that group; for instance, if a call occurs on one of the incoming trunks and the first register sender 900 is idle, the group relay 304 is operated, but if the first sender is busy and the second sender 915 is idle, then the group relay 115 305 is energized instead. The selection of the proper one of the ten units relays depends upon the units designation of the trunk on which the call appears and also 120 125

upon the particular sender which is to be associated with such trunk. If the call appears on the first trunk of the group and the first sender is idle, then the No. 1 units relay 608 is operated in conjunction with the group relay 304, whereas if the third trunk calls instead, the No. 3 units relay 608 becomes energized. On the other hand, should be first sender be engaged when a call is extended over trunk No. 1, the No. 1 units relay 613 is operated in conjunction with the group relay 305 individual to the second sender, and so on.

Considering the second group of ten incoming trunks, of which one is shown diagrammatically in Fig. 4, the senders of the group normally serving these are arranged to be associated in identical manner. Relay 406 is the group relay individual to the second group of trunks, through the armature contacts of which the controlling conductors for each of the ten incoming trunks are extended to the contacts of the units relays individual to the first sender of the second group of senders. The multi-contact group relay 407 is also individual to the second group of trunks and has for its function to associate the second register sender of the second group with any of the ten trunks. The ten units relay 706, 707, 708, etc. are each individual to the ten trunks of the group and also to the first register sender.

The same arrangement is true with respect to the third group of ten trunks, one of which 501, 502 is shown in Fig. 5. Here the two group relays 510 and 511, associated with this group of trunks, serve respectively for associating the two register senders of the third group with the ten trunks of the third group of trunks. The same plan may be extended throughout the twelve different groups, according to the assumption, or to as many groups as the system embraces. Only three complete groups have been shown, however, inasmuch as a further duplication of the disclosure is unnecessary for an understanding of the invention.

According to an important feature of this invention a circuit relation between the several individual groups is employed whereby the register senders of the several groups, which normally serve the trunks with which they are associated, may also be taken for use under certain conditions in connection with the trunks of any of the remaining groups. That is to say, should a connection be extended over one of the trunks in the first group at a time when both register senders 900 and 915, normally serving that group, are busy, the first idle sender in the succeeding group may be taken for use and associated with the calling trunk. Should the first sender and all succeeding senders in the second group likewise be busy at the time, then the first idle sender in the third group

may be taken for use. Such an arrangement it will be seen enables a normal individual association of the senders with the different groups of trunks and at the same time permits a universal use of all senders in connection with the trunks of all groups. To this end the first group of trunks 121, 122 and 301, 302, etc., in addition to being provided with their respective group relays 304 and 305, are also provided at each of the remaining eleven groups of trunks with corresponding group relays. At the second group the relays 404 and 405 are individual to the first group of ten trunks and serve to associate respectively the two senders normally allotted to the second group of trunks with the trunks of the first group. At the third group the relays 504 and 505 are individual to the first group of trunks and operate respectively to associate the two senders normally allotted to the third group of trunks with the trunks of the first group. Similarly, the second group of ten trunks is provided at the first group with the two individual group relays 306 and 307 which serve respectively to associate the senders 900 and 915 with the trunks of said second group. The same relation exists throughout all the remaining groups of trunks, namely that every group has at every other group of trunks as many individual group relays therefor as there are senders in a group of senders. It will be noted that the conductors 227, 228 and 229 of the first trunk in the first group which lead to the armatures of the group relay 304 also lead to the armatures of each of the group relays 404, 504, etc., individual to the first group of trunks at all remaining groups. In like manner these three conductors, which extend to the armatures of relay 305, are multiplied to corresponding armatures of the group relays 405, 505, etc. at all other groups. The same relation of multiple wiring between the armatures of the group relays throughout the entire twelve groups also exists with respect to all other trunks.

Consequently, should a connection be extended, for example, over the first trunk 121, 122 of the first group when both senders 900, 915 normally used in connection with this group are busy, a condition is brought about for the energization of group relay 404 individual to the first group of trunks at the second group, and for the energization of the units relay 706 individual to the first sender of the second group provided this sender is idle. The calling trunk is thereby connected through the contacts of relay 404 and relay 706 to an idle sender in the second group and this sender thereupon operates to control the establishment of the connection. If all senders in the second group are busy as well as all senders in the first group, then the initiation of a call on a trunk in the first

group of trunks causes the energization of the relay 504 at the third group of trunks and the energization of the corresponding units relay individual to the first idle sender 5 in the group normally serving the third group of trunks, and this idle sender is associated with the calling trunk.

By the use of these coordinate connecting relays it will be observed that the register 10 senders are instantaneously connected to a trunk line upon the extension of the connection over that trunk to the distant office whether the sender taken belongs to the group normally serving the group containing 15 the calling trunk or to some other group of senders. The necessity of a quick attachment of the senders to the trunks arises from the fact that only a short interval of time is available between the completion of trunk 20 hunting in the calling office and the transmission of the next succeeding series of impulses from the calling subscriber's dial. The sender must be attached before this 25 series of impulses is sent in order that they may be properly recorded thereon.

After all series of impulses have been transmitted over the trunk and recorded on the registers of the associated sender, this 30 sender becomes effective in the well-known manner to control the selective movements of the incoming selector switch 224 and the final selector 225 to complete the extended connection to the terminals of the called line. A general description having thus been 35 given of the grouping arrangement utilized in this system, it is believed that a more thorough understanding is to be had of the invention from a detailed description of the operating circuits.

For this purpose it will be assumed that 40 the subscriber of line 100 in the originating office desires to obtain a telephone connection with the subscriber's line 200 in the distant office. Upon removing his receiver from the 45 switch hook the subscriber at substation 100 causes the operation of the individual switch, which automatically drives its brushes 102, 103, 104 to the terminals 105, 106, 107 of the trunk leading to a first group 50 selector switch. The subscriber thereupon manipulates his sending dial 101 to transmit a series of impulses causing the first group selector to operate in a step-by-step manner to select and seize the terminals 111, 112, 113 55 of an outgoing trunk 121, 122 leading to the desired distant office which is equipped with switches of the power driven type. Immediately that the brushes 108 and 109 arrive upon the terminals 111, 112 of the trunk, a 60 circuit is closed from battery through the upper winding of relay 114, upper normal contacts of relay 115, terminal 111, brush 108, terminal 105, brush 102, thence over the loop of the calling line and returning by 65 way of brush 103, terminal 106, brush 109,

terminal 112, normal contacts at the inner lower armature of relay 115, lower winding of relay 114 to ground. Relay 114 closes a circuit for relay 116. With relays 114 and 116 energized a circuit is established from 70 battery through the left-hand winding of relay 203 at the distant office, lower back contact of relay 202, contact of sequence switch spring 207 (1 + 9), conductor 122, conductor 123, lower contact of relay 114, right-hand winding of relay 119, normal contact at the lower armature of relay 115, conductor 120, upper winding of relay 118, back contact of relay 117, uppermost contact of relay 116, conductor 121, contact of spring 80 206 (1 + 9), upper back contact of relay 202, winding of retardation coil 201 to ground. It will also be noted that the relay 116 upon energizing completes a circuit through the lower winding of relay 118. 85 Relay 118 is so constructed as not to operate due to the flux created by its lower winding alone, and is also arranged such that it fails to operate when the lower winding is energized and when current flows through the 90 upper winding in a given direction. The current in the circuit just traced over the trunk 121, 122 through the upper winding of differential relay 118 is in the wrong direction for causing the operation of said relay. 95 Consequently, relay 118 remains inert.

The relay 203 at the distant office upon energizing closes a circuit for relay 209. Relay 203 also closes a circuit from ground through its outer contact and armature, left 100 back contact of relay 208, conductor 226, winding of relay 600, winding of relay 612 to battery. The relay 600 is individual to the first trunk in the group of ten trunks, namely to the trunk 121, 122. In a similar 105 manner relay 601 is individual to the second trunk 301, 302 in the first group, while relay 602 is individual to the third trunk. The remaining relays individual to the remaining trunks have not been shown. In the circuit 110 above traced the relays 600 and 612 become energized and a circuit is thereupon established from battery to the left-hand winding of relay 603, front contact of relay 600, outer left contact of relay 618, outer left contact 115 of relay 619, conductor 636, and thence to the conductor similarly identified in Fig. 8, to ground at the outer right back contact of relay 800.

It will be well to explain at this point that 120 where only three groups of trunks have been illustrated in the present disclosure instead of all twelve groups, it is assumed that the several conductors, which terminate on the left-hand side of Fig. 6, are joined in corresponding conductors terminating on the right-hand side of Fig. 8. Several of these 125 conductors, namely those most likely to be considered in the following discussion, are terminated in small circles bearing letters of 130

the alphabet in order to facilitate their identity.

The reason for extending the energizing circuit of relay 603 through the armature and contact of relay 800 of the preceding group is to test the condition of such preceding group to insure that it is not in the act of appropriating one of the senders in the group normally serving the calling group of trunks. This will be brought out more clearly hereinafter. Relay 603, therefore, becomes energized and closes a circuit from battery through its right-hand winding and right front contact, winding of relay 618, outer left contact of relay 619, and thence to ground at relay 800 as traced. Relay 618 operates in series with relay 603.

It is taken for granted that the first sender 900 is idle at this time. Relay 618 in operating closes a circuit from ground through its outermost right contact, right armature and back contact of relay 619, inner right armature and back contact of relay 621, conductor 625, conductor 634, contact 912 of the sender sequence switch 910 closed in position 1, conductor 635, left back contact of relay 610, winding of relay 609 to battery. Relay 609 is the allotting relay individual to the sender 900 and through its armature contacts prepares circuits to each of the group relays 304, 306, 310, etc. individual to the first group of trunks. Relay 609 in operating also establishes a circuit from battery through the winding and contact of said relay, conductors 637 and 638, outer left armature and back contact of relay 621, winding of relay 619 to ground at the outermost right contact of relay 618. Relay 619, included in this circuit, does not operate in view of the shunt closed around its winding through the left armature and back contact of relay 610. In addition to preparing circuits through the windings of group relays 304, 306, 310, etc., the allotter relay 609 also prepares circuits to each of the ten units relays 606, 607, 608, etc. individual to the first sender 900. A circuit may now be traced from ground through the middle right contact of relay 618, conductor 626, contact 638 of relay 609, conductor 639, winding of relay 304 to battery. Relay 304 operates and locks in a circuit from battery through its winding and right contact, conductor 322 to ground at the contact 640 of relay 609. Furthermore, a circuit is closed from ground through the inner right contact of relay 618, left contact of relay 603, conductor 641, contact 642 of relay 609, winding of relay 606 to battery. The units relay 606 locks in a circuit from battery through its winding and right contact, conductor 322 to ground at contact 640. With both the group relay 304 and the units relay 606 energized, the three controlling leads 227, 228 and 229 of the trunk 121, 122 are extended through

to the register sender 900. Therefore, a circuit is established from ground through the outer right contact of relay 209, lower left contact of spring 215 (1+9), left-hand winding of relay 208, conductor 229, contact 323 of relay 304, conductor 318, outermost left contact of units relay 606, winding of relay 610 to battery. Relays 610 and 208 become energized. Relay 208 locks in a circuit from battery through its right-hand winding and inner right contact, outer right contact of relay 209 to ground. Relay 208 at its left back contact opens the energizing circuit of relay 600 individual to the trunk 121, 122, permitting this latter relay to release.

It will be noted that at the time relay 209 operates a circuit is completed from battery through the winding of relay 212, upper right contact of spring 215 (1+1), outer right contact of relay 209 to ground. Relay 212 operates in this circuit.

Relay 610, which also operates in series with relay 208 at its left armature and contact, opens the shunt around the winding of relay 619 permitting this latter relay to operate. Relay 619 upon operating opens the circuit for relays 603 and 618 and these relays deenergize. Relay 618 in turn opens the circuit of relays 609 and 619 which also become deenergized. Relay 609 cannot again operate since its energizing circuit is held open at the left back contact of relay 610. Relays 304 and 606 are now held energized in their locking circuits which extend to ground at the right front contact of relay 610 instead of through the contact 640 of relay 609.

The register sender 900 has thus been attached to the trunk 121, 122 and the operations involved in the connection have taken place within the very brief interval following the closure of the trunk at the repeater in the calling office. When the calling subscriber manipulates his dial 101 to transmit the next series of impulses corresponding, for example, to the second digit in the called designation, the relay 114 is deenergized and energized in succession to cause the repetition of the impulses over the outgoing trunk circuit. Upon the first opening of the subscriber's line relay 114 releases its armatures and a circuit is closed from ground through the upper back contact of said relay, inner upper contact of relay 116, winding of relay 117 to battery. Relay 116 being slow to release does not become deenergized during the intervals in which its circuit is open at the upper front contact of relay 114 in the transmission of impulses. Likewise, relay 117 is of the slow to release character and remains operated during the brief intervals in which its winding is open at the upper back contact of relay 114.

Relay 114 at its lower contact opens the circuit traced over trunk 121, 122 through the left-hand winding of relay 203. At the time relay 208 operates it closes a circuit 5 from battery through the two windings of relay 203 in series, left front contact of relay 208, outer contact of relay 203 to ground. The relay 203 is so constructed that the right-hand winding produces a 10 differential effect. While the flux set up due to the energization of the right-hand winding is not sufficient to differentiate the flux caused by the left-hand winding, it does operate as soon as the circuit of the 15 left-hand winding is opened to effect a quick release of the armatures. Consequently, upon the opening of the operating circuit through the left-hand winding of relay 203, the relay immediately retracts 20 its armatures. Relay 209 being slow to release does not retract its armatures during the brief intervals that its circuit is open at the inner front contact of relay 203. A circuit is now completed from ground 25 through the inner back contact of relay 203, inner contact of relay 209, conductor 227, contact 324 of relay 304, conductor 316, innermost left contact of relay 606, conductor 633, left-hand winding of relay 901 to battery. Relay 901 operates and completes a circuit from ground through its contact, brush 904 of the register control switch (position 1), winding of register 30 stepping magnet 906, winding of slow-to-release relay 911 to battery. Magnet 906 becomes energized preparatory to advancing 35 the brushes of the first register one step forward.

One of the brushes and the terminal bank 40 with which it cooperates for the first register is designated by the character 916. One of the brushes of each of three succeeding registers and its cooperating terminal bank is also diagrammatically illustrated in the 45 drawing. These are shown at 917, 918 and 919, respectively. It is understood, of course, that there will be as many registers as desired. For controlling the successive association of the impulse relay with the 50 several registers and for controlling other functions involved in the operation of the sender, a register control switch is provided which, like the registers themselves, consists of a single motion step-by-step switch. Three of the brushes 903, 904 and 905 and their cooperating terminal banks 55 are shown for the register control switch. These brushes are stepped forward by a stepping magnet 902 and are arranged to be advanced upon deenergization of the magnet.

The slow-to-release relay 911, which, as 60 above described, becomes energized in series with the stepping magnet 906 for the first 65 register, completes a circuit from ground

through its contact, winding of magnet 902 to battery. The magnet 902 energizes and prepares to advance the brushes 903, 904 and 905 forward one step upon deenergization. At the end of the first impulse 70 the subscriber's line circuit is closed and relay 114 again energizes. Relay 203 is now operated in a circuit from battery through its left-hand winding, thence over the conductor 122, as hereinbefore traced, 75 conductor 123, lower contact of relay 114, conductor 124, front contact of relay 117, uppermost contact of relay 116, conductor 121, and thence to ground through the retardation coil 201. This circuit excludes 80 the upper winding of the differential relay 118, but this relay still remains deenergized due to the fact that current flowing through the lower winding thereof is insufficient to operate the same. Relay 203 on operating 85 opens the circuit of the relay 901 at the sender, which in turn deenergizes and opens the circuit through the stepping magnet 906 and relay 911. Magnet 906 deenergizes and advances the brushes of the first register, 90 of which brush 916 is one, forward to their first position contacts. Relay 911, however, being slow to release maintains its armature attracted. This procedure continues 95 for each impulse in the series until all impulses have been completed from the calling subscriber's line. After the proper interval has elapsed following the last closure of the subscriber's line, during which time 100 relays 114 and 203 are maintaining their 105 armatures attracted, the slow-to-release relays 117 and 911 become deenergized. Relay 117 establishes the previously traced circuit over the trunk including the upper winding of the differential relay 118 and the left-hand winding of relay 203. Current 110 still flows in the wrong direction, however, to cause the energization of the differential relay 118. Referring to the sender the relay 911 upon deenergizing opens the circuit of 115 the register control stepping magnet 902 which releases and advances the brushes 903, 904 and 905 on to their second position terminals.

During the transmission of the next series 115 of impulses, representing the next digit in the called designation, relays 114, 203 and 901 respond in the manner previously described and the stepping magnet 907 is successively operated to advance the brushes of 120 the second register from one position to another. The circuit for magnet 907 extends from ground through the contact of relay 901, brush 904 (position 2), winding of magnet 907, winding of relay 911 to battery. Relay 911 remains energized during 125 the transmission of impulses, holding the circuit closed through the winding of magnet 902. At the end of the impulse series the second register has been set in its proper 130

- position and the slow-to-release relay 911 becomes deenergized to advance the register control switch into its third position. Likewise, for each of the following series of impulses representing the remaining digits of the called designation, the corresponding registers of the sender 900 are selectively positioned. After the subscriber has completed his dialing operation, the slow-to-release relay 117 deenergizes and the circuit of the trunk conductors 121, 122 is established including the left-hand winding of relay 203 and the upper winding of the differential relay 118.
- 15 Following the completion of the setting of the registers of the sender, the controlling sequence switch 910 is advanced to a position for establishing the fundamental circuit for controlling brush selection at the 20 incoming selector switch 224. The fundamental circuit may be traced from battery through the winding of relay 213 (Fig. 2), lower right contact of spring 219 (1+10), upper left contact of said spring (1), right 25 contact of spring 214 (1+9), inner left front contact of relay 212, outer right contact of relay 208, conductor 228, contact 325 of relay 304, middle left contact of relay 606, conductor 632, contact of spring 913 of sequence switch 910, contact of counting relay 921, winding of stepping relay 914 to ground. Relay 213 becomes energized and closes a circuit from battery through the winding of sequence switch 35 magnet 210, contact of spring 217 (1), inner contact of relay 213 to ground, driving said sequence switch out of position 1 and into position 2. In position 2 a circuit is prepared from battery through the winding 40 of the updrive power magnet 211, contact of spring 218 (2), inner contact of relay 213 to ground. In the well-known manner the power magnet 211 causes the brush shaft of the incoming selector switch 224 to be driven upwardly for the purpose of determining the selection of the proper set of brushes. The stepping relay 914, which operates intermittently in the fundamental circuit, causes the counting relays to be successively energized in accordance with the 45 registration on the registers, until finally the fundamental circuit is opened by counting relay 921 at which time the brush shaft has reached a position for the selection of the proper set of brushes. The relay 213 now becomes deenergized and opens the circuit of power magnet 211, and also in the well-known manner causes the advance of sequence switch 210.
- 50 Following the brush selection, the incoming switch 224 is caused to perform its group selecting operation and thereafter trunk hunting ensues and a trunk is chosen leading to an idle final selector switch 225. 55 Brush selection tens and units selections

next proceed at the final switch 225 under the control of the register sender and the connection is extended through to the terminals of the called subscriber's line 200.

During the period in which the register sender is attached to the incoming trunk and is positioned by impulses transmitted from the originating office, and also during the selective movements of the incoming and final switches, the sequence switch 210 is 70 in its successive positions from 1 to 9. Following the completed extension of the connection the sequence switch 210 advances out of position 9 into its talking position, which may be assumed as position 16. On leaving 80 position 9 it is to be noted that the contacts of springs 206 and 207 are open, whereby the circuit of relay 203 now extends from battery through the left-hand winding thereof, lower back contact of relay 202, lower left-hand winding of repeating coil 204, conductor 122 to the originating office and returning by way of conductor 121, upper left-hand winding of repeating coil 201, upper back contact of relay 202, winding of retardation coil 201 to ground. The left-hand windings of the repeating coil 204 are thus included in the talking circuit, having been shunted out during the transmission of impulses by springs 206 and 207 in 90 order to obviate their detrimental effect upon the operating impulses.

When the called subscriber responds by removing his receiver from the switch hook, 100 a circuit is established in the well-known manner for the operation of the supervisory relay 205. Relay 205 closes a circuit for relay 202 which becomes energized and modifies the circuit of relay 203 in such a manner that battery is now connected through the 105 left-hand winding of this latter relay to the conductor 121, instead of as originally to the conductor 122. This reversal of current over the trunk and through the upper winding of differential relay 118 produces a 110 cumulative effect in said relay whereby it receives sufficient energy to attract its armatures. Relay 118 upon operating completes a circuit from ground through its lowermost contact and winding of relay 115 to battery. 115 Relay 115 operates and modifies the circuit of relay 114 so that current now flows from battery through the upper winding of relay 114, inner lower armature and contact of relay 115, terminal 112, brush 109, thence 120 over the lower side of the talking circuit through the loop of the calling subscriber's line and returning over the upper side of the talking circuit to the terminal 111, contact and upper armature of relay 115, lower 125 winding of relay 114 to ground. This reversal of current may be utilized in the well-known manner for operating a polarized message register individual to the calling subscriber's line.

At the termination of conversation the subscribers replace their receivers on the switch hooks and all switches utilized in the establishment of the connection are restored 5 to their normal positions in the usual manner.

Should the first sender 900, which normally serves the first group of ten trunks, be busy when the connection is extended 10 over trunk 121, 122, then the next sender 915 of the group is taken for use provided the same is idle. The same, of course, is true regardless of what particular one of the ten trunks of the first group receives 15 the call, and in order to illustrate this it will next be considered that the call from the originating office was extended over the second trunk 301, 302 of the group to the incoming selector switch 300 in the distant 20 office and that sender 900 is busy at the time. Immediately that the connection is extended over trunk 301, 302, a circuit is closed as previously traced for the left-hand winding of relay 303, which, it will be noted, corresponds 25 to relay 203 of the first trunk. Relay 303 operates and closes a circuit for relay 309. Relay 303, furthermore, establishes a circuit from ground through its outer right contact, left back contact of relay 308, 30 conductor 314, winding of the second units relay 601, individual to the second trunk in the group 301, 302, winding of relay 612 to battery. Relay 601 closes a circuit from battery through the left-hand winding of 35 relay 604, front contact of relay 601, back contact of relay 600, outer left contact of relay 618, outer left contact of relay 619, conductor 636, thence to conductor 636, Fig. 8, outer right back contact of relay 800 to ground. Relay 604 operates and closes a 40 circuit from battery through its right-hand winding and right front contact, right back contact of relay 603, winding of relay 618, outer left contact of relay 619, conductor 636, and thence to ground as traced. Relay 45 618 operates and establishes a circuit from ground through its outermost right contact, right armature and back contact of relay 619, inner right back contact of relay 621, conductor 625, conductor 634, upper contact of spring 912 (2+18) (the sequence switch 910 being in some position other than position 1 due to the fact that sender 900 is busy), left contact of spring 934 (1), 50 conductor 935, right back contact of relay 616, winding of relay 617 to battery. The allotting relay 617, individual to the second sender 915, is thereupon energized and closes a circuit from battery through its winding 55 and contact, conductor 638, outer left back contact of relay 621, winding of relay 619 to ground at the outermost right contact of relay 618. Relay 619, however, remains deenergized since its winding is shunted by the direct circuit to ground closed through 60

the right back contact of relay 616. Relay 617 attracts its armatures and prepares circuits for each of the group relays 305, 307, 311, etc., individual to all groups of incoming trunks. Relay 617, furthermore, prepares circuits for each of the ten units relays 613, 614, 615, etc. individual to the second sender 915. A circuit is now established from ground through the middle right contact of relay 618, conductor 626, 75 contact 642 of relay 617, conductor 643, winding of group relay 305 to battery. Relay 305 operates and locks in a circuit from battery through its winding and right contact, conductor 315 to ground through the 80 contact 644 of relay 617. A circuit is also closed from ground through the innermost right contact of relay 618, left contact of relay 604, conductor 645, contact 646 of relay 617, winding of the No. 2 units relay 85 614 to battery. Relay 614 operates and locks in a circuit from battery through its winding and left contact, conductor 315 to ground through contact 644 of relay 617.

With relays 305 and 614 operated the second register sender 915 of the group is connected to the second trunk 301, 302. A circuit is closed from ground through the outer contact of relay 309, conductor 330, thence, as described in connection with the first trunk shown in Fig. 2, to conductor 331, left-hand winding of relay 308, conductor 329, contact 332 of relay 305, conductor 333, outermost right contact of relay 614, winding of relay 616 to battery. Relay 308 becomes energized and opens the circuit above traced for relays 601 and 612; causing these relays to become deenergized. Relay 616 also operates and removes the shunt from around the winding of relay 619. Relay 619 100 thereupon attracts its armatures and in so doing opens the circuit of relays 604 and 618. These relays both deenergize and relay 618 in turn opens the circuits of relays 619 and 617. Relays 617 upon deenergizing 105 opens the original holding circuits of relays 305 and 614, but these relays remain locked in the circuits previously traced through their winding and contacts to conductor 315 from whence it leads to ground through the 110 left front contact of relays 616.

The impulse series set over the line from the calling subscriber's station now operate the relay 922 at the sender 915, which in turn causes the successive operation of the stepping magnets 927, 928, 929 and 930 to position the registers in the sender in accordance with the digits of the desired designation. The slow-to-release relay 931 serves in conjunction with the stepping magnets 115 to cause the progressive advance of the brushes 923, 925 and 926 of the register control switch. The sender 915 thereafter becomes effective to cause the setting of the incoming selector switch 300, and a final 120 125 130

selector switch to extend the connection through to the called line.

The next case to be considered is the one wherein a connection is extended over the first trunk 121, 122, for example, in the first group when both register senders 900 and 915 normally serving that group are busy. In this instance the start circuit for the energization of an allotting relay is extended through to the group of senders normally serving the second group of trunks. The extension of the connection over trunk 121, 122 causes, in the manner previously explained, the energization of the No. 1 units relay 600. Relay 600 operates and prepares a circuit from battery through the left-hand winding of relay 603, front contact of relay 600, outer left contact of relay 618, outer left contact of relay 619, conductor 636, and thence to ground at the outer right back contact of relay 800. Relay 603 energizes and a circuit is closed from battery through the right-hand winding and right front contact of relay 603, winding of relay 618, outer left contact of relay 619, conductor 636 to ground as described. Relay 618 operates and completes a circuit from ground through the outermost right contact of said relay, right-hand armature and back contact of relay 619, inner right back contact of relay 621, conductor 625, conductor 634, upper contact of spring 912 (2+18), right contact of spring 934 (2+18), conductor 936, outer right contact of relay 621, conductor 647, contact 713 of relay 711, conductor 725, conductor 715, upper contact of spring 740 (1) of the controlling sequence switch of the first sender normally serving the second group of trunks, conductor 716, left back contact of relay 710, winding of allotting relay 709 to battery. Relay 709 operates and closes a circuit from battery through its winding and right contact, conductor 717, contact 720 of relay 711, conductor 650, inner left contact of relay 621, outer left back contact of said relay, winding of relay 619 to ground at the outermost right contact of relay 618. Relay 619, however, does not energize in this circuit so long as its winding is shunted by the circuit previously traced through the left back contact of relay 710. The allotting relay 709, upon attracting its armatures, completes a circuit from ground through the middle right contact of relay 618, conductor 626, contact 721 of relay 711, contact 722 of relay 709, conductor 723, winding of group relay 404 to battery. Relay 404 operates and locks in a circuit from battery through its winding and right contact, conductor 403, contact 724 of relay 709, to ground. A second circuit is completed from ground through the innermost right contact of relay 618, left contact of relay 603, conductor 641, contact 730 of relay 711, contact 731 of relay 709, winding of No. 1 units relay 706 to battery. Relay 706 operates and locks through its right contact to the grounded conductor 403. Following the operation of relay 706, a circuit is closed from ground through the outer contact of relay 209, lower left-hand contact of spring 215 (1+9), left-hand winding of relay 208, conductor 229, contact 408 of relay 404, conductor 409, outermost left contact of relay 706, winding of relay 710 to battery. Relay 710 operates and opens the shunt circuit which has been preventing the energization of relay 619. Relay 619, therefore, operates in series with relay 709. Relay 619, in the manner previously described, opens the circuit of relays 603 and 618 which become deenergized, relay 618 in turn opening the circuit of relays 619 and 709 permitting them to deenergize. Relays 612 and 600 retract their armatures at the time relay 208

65 Relay 620 upon operating completes a circuit from ground through its outer right front contact, conductor 649, winding of re-

operates in the circuit just traced including relay 710. At the time relay 619 operates it modifies the circuit of relay 620 as follows: battery, through the winding of relay 620, left back contact of relay 622, make-before-break contact at the right-hand armature of relay 619, outermost right contact of relay 618 to ground. Consequently, relay 620 remains operated to maintain the 10 operation of relay 711 during the period that relay 619 is energized and until relay 618 becomes deenergized. Immediately, however, that relay 618 retracts its armatures, relay 620 releases and permits the 15 release of relay 711. Relay 709 upon deenergizing opens the holding circuit of relays 404 and 706, but these relays remain operated in a new holding circuit closed over conductor 403 to ground through the right 20 front contact of relay 710.

The control conductors 227 and 228 of the first trunk 121, 122 are now extended by way of contacts 412 and 413 of relay 404, conductors 414 and 415, innermost and middle left contacts of relay 706, conductors 25 732 and 733 to the selected sender. This sender is next positioned in accordance with the incoming impulses and functions to determine the selective operations of the incoming and final switches to complete the 30 establishment of the connection to the desired called line.

Should the first sender normally serving the second group of trunks be busy as well as both senders 900 and 915, which normally serve the first group of trunks at the time the call appeared on one of the trunks of the first group, then the starting circuit is extended through to the second 35 sender of the second group. This starting circuit leads, as above explained, from ground through the outermost right contact of relay 618, right armature and back contact of relay 619, inner right back contact 40 of relay 621, conductor 625, conductor 634, upper contact of relay 912 (2 + 18), right contact of spring 934 (2 + 18), conductor 936, outer right contact of relay 621, conductor 647, contact 713 of relay 711, conductor 725, conductor 715, lower contact of spring 740 (2 + 18), left contact of 45 spring 741 (1) of the sequence switch controlling the second register sender, conductor 735, right back contact of relay 736, winding of allotting relay 737 to battery. The relay 737 functions in the same manner and for the same purpose as relays 709, 617 and 609, hereinbefore described. Should it happen that all senders in both the first 50 and second groups were busy at the time a call occurred on one of the trunks in the first group, then a sender in the third group is chosen if one is busy, and if not, in some succeeding group by the same process as that already explained in detail.

It might happen that there were idle senders in the group normally serving the group of trunks at the time a call is made therein, but for some reason or other the idle sender fails to be attached to the calling trunk. If, therefore, an idle sender is not associated with a calling trunk within a predetermined interval of time following the extension of a connection over such trunk, a condition is brought about 70 for testing the next succeeding group of senders and choosing an idle one therein for use. At the time the call is extended over the trunk 121, 122, the relay 612, which is common to all of the ten trunks in the group, is operated in series with the units relay 600. Relay 612 also operates in series with any of the remaining nine units relays. Relay 612 completes a circuit from ground through its contact, conductor 651, thence 75 to conductor 651, Fig. 8, inner right back contact of relay 800, which relay it will be recalled is individual to the preceding group, conductor 652, thence to conductor 652, Fig. 6, right back contact of relay 624, winding of relay 623 to battery. Relay 623 80 operates and closes a circuit from ground over conductor 652, front contact of relay 623, winding of relay 624 to battery. Relay 624 on operating opens the circuit of 85 relay 623. Relay 623, which is slow to deenergize, retracts its armature after the lapse of a given interval of time. Upon 90 the restoration of relay 623, relay 624 remains operated in a locking circuit from 95 battery through its winding and right front contact to the grounded conductor 652. A circuit is now completed from ground over conductor 652, back contact of relay 623, inner left contact of relay 624, winding of 100 relay 622 to battery. Relay 622 attracts its 105 armatures and closes a circuit from ground through its left front contact, winding of relay 620 to battery. Relay 620 operates and a circuit is established from battery 110 through the winding of relay 621, left contact of relay 620, right contact of relay 622 to ground. Relay 620 also causes, as previously explained, the operation of relay 711. With relays 621 and 711 operated the start 115 circuit is now extended from ground through the outermost right contact of relay 618, right armature and back contact of relay 619, inner right front contact of relay 621, conductor 647, contact 713 of relay 711, and thence to the allotting relay of 120 the first idle register sender in the second group, as previously traced. Assuming the first sender to be idle, the allotting relay 709 is operated and completes a circuit from battery through its winding and right contact, conductor 717, contact 720 of relay 711, conductor 650, outer right front contact of relay 621, winding of relay 619, to ground at the outermost right contact of 125 130

relay 618. From this point on the association of the sender with the calling trunk is the same as already described.

According to another important principle 5 of the invention, it is possible for one of the interoffice trunks to be released at the step-by-step office and immediately be selected again by some other switch prior to the time that the incoming selector 224 of the distant office has fully restored to its normal 10 position. If in a case of this kind the attachment of an idle sender were delayed until the incoming selector had completely restored, one and perhaps more of the series 15 of impulses transmitted from the calling substation, calculated to set the register sender, would be lost or mutilated. For this reason the circuits are so designed that a sender may be attached immediately upon 20 selection of the trunk at the calling office and receive the incoming impulses regardless of the condition of the power-driven switch in which the trunk terminates at the distant office. Consider, for example, that 25 the trunk 121, 122, having just been released by the selector switch whose brushes are represented at 108, 109, 110, is immediately seized by the same or another similar selector switch, while the incoming selector 30 224 at the distant end of the trunk is undergoing restoration. The controlling sequence switch 210 is, therefore, in some position between positions 16 and 1, inasmuch as position 16 was assumed the talking position. If the trunk had been released prematurely, the sequence switch 210 might 35 then be in some position between 10 and 1. In either event the contact springs 206 and 207, through which impulses are normally 40 transmitted to the relay 203, are opened. Immediately that the trunk 121, 122 is released at the calling office, relay 203 becomes deenergized to permit the release of relay 209. Relay 209 opens the holding circuit of 45 relay 212 and this relay upon releasing prepares an impulse circuit for the relay 203 in substitution of the circuit which normally leads through the contacts of springs 206 and 207. When, therefore, the trunk 121, 50 122 is again closed during the time sequence switch 210 is somewhere between positions 10 and 1, the relay 203 is operated in a circuit from battery through its left-hand winding, lower back contact of relay 202, conductor 223, inner left back contact of 55 relay 212, left contact of spring 214 (10+18), conductor 122, thence over the trunk circuit and returning by way of conductor 121, conductor 221, outer left contact of relay 212, conductor 222, upper back contact of relay 202, winding of retardation coil 201 to ground. In this circuit the relay 203 operates in the manner previously described 60 to cause the attachment of an idle register sender and to repeat the incoming pulses 65

thereto to cause the setting of the controlling registers. If the sequence switch 210 reaches its normal position either during the attachment of the sender or during the setting of the registers, the springs 209 and 210 are closed and the usual impulse circuit is prepared for the relay 203. At the same time relay 212 is operated in a circuit closed at the upper right contact of spring 215 (1+1½) to ground at the outer contact of 70 relay 209. Relay 212 thereupon energizes and opens the impulse circuit of relay 203 which was temporarily used during the restoration of the switch. This transition from the temporary circuit to the normal 75 circuit for the operation of relay 203 occurs without interruption and without detriment to the controlling impulses incoming over the trunk 121, 122.

What is claimed is:

1. In a telephone system, a plurality of groups of trunks, a plurality of senders, one associated with each group of trunks, each of said senders being arranged normally to serve the group of trunks with which it is associated, means for connecting said senders to the trunks of the groups they normally serve, and means for connecting one of said senders to the trunks of some group other than the one it normally serves. 85
2. In a telephone system, a plurality of groups of trunks, a plurality of senders, one associated with each group of trunks, each of said senders being arranged normally to serve the group of trunks with which it is associated, means for connecting said senders to the trunks of the groups they normally serve, and means for connecting any one of said senders to the trunks of any one of said groups. 90
3. In a telephone system, a plurality of groups of trunks, a plurality of senders, one associated with each group of trunks, each of said senders being arranged normally to serve the group of trunks with which it is associated, means for connecting said senders to the trunks of the groups they normally serve, and means when the sender normally serving a particular group of trunks is busy for connecting another of 100 said senders to the trunks of said particular group. 105
4. In a telephone system, a plurality of groups of trunks arranged in succession, a plurality of senders, one associated with each of said successive groups of trunks, each of said senders being arranged normally to serve the group of trunks with which it is associated, means for connecting said senders to the trunks of the groups they normally serve, and means when the sender normally serving a particular group of trunks is busy for connecting the next successive idle sender to the trunks of said particular group. 110
5. In a telephone system, a plurality of groups of trunks arranged in succession, a plurality of senders, one associated with each of said successive groups of trunks, each of said senders being arranged normally to serve the group of trunks with which it is associated, means for connecting said senders to the trunks of the groups they normally serve, and means when the sender normally serving a particular group of trunks is busy for connecting the next successive idle sender to the trunks of said particular group. 115
6. In a telephone system, a plurality of groups of trunks arranged in succession, a plurality of senders, one associated with each of said successive groups of trunks, each of said senders being arranged normally to serve the group of trunks with which it is associated, means for connecting said senders to the trunks of the groups they normally serve, and means when the sender normally serving a particular group of trunks is busy for connecting the next successive idle sender to the trunks of said particular group. 120
7. In a telephone system, a plurality of groups of trunks arranged in succession, a plurality of senders, one associated with each of said successive groups of trunks, each of said senders being arranged normally to serve the group of trunks with which it is associated, means for connecting said senders to the trunks of the groups they normally serve, and means when the sender normally serving a particular group of trunks is busy for connecting the next successive idle sender to the trunks of said particular group. 125
8. In a telephone system, a plurality of groups of trunks arranged in succession, a plurality of senders, one associated with each of said successive groups of trunks, each of said senders being arranged normally to serve the group of trunks with which it is associated, means for connecting said senders to the trunks of the groups they normally serve, and means when the sender normally serving a particular group of trunks is busy for connecting the next successive idle sender to the trunks of said particular group. 130

5. In a telephone exchange system, a plurality of groups of trunks, a plurality of groups of senders, one associated with each group of trunks, the senders of each of said groups being arranged normally to serve the trunks of the group with which they are associated, means for connecting said senders to the trunks of the group they normally serve, and means for connecting any 10 sender in any group of senders with the trunks of any group of trunks.
6. In a telephone exchange system, a plurality of groups of trunks, a plurality of groups of senders, one associated with each group of trunks, the senders of each of said groups being arranged normally to serve the trunks of the group with which they are associated, means for connecting said senders to the trunks of the group they 15 normally serve, and means when all senders of the group normally serving a particular group of trunks are busy for connecting a sender in some other group to the trunks of said particular group of trunks.
7. In a telephone system, a plurality of groups of trunks, selective switches for extending said trunks to establish telephone connections, a plurality of groups of senders, one associated with each group of trunks, the senders of each group being arranged normally to serve the trunks of the group with which they are associated, means for connecting said senders to the trunks of the group they 20 normally serve, means for connecting the senders of a given group to the trunks of groups other than the one they normally serve, and means controlled by said senders for operating the selective switches.
8. In a telephone system, a plurality of groups of trunks, selective switches for extending said trunks to establish telephone connections, a plurality of groups of senders, one associated with each group of trunks, the senders of each group being arranged normally to serve the trunks of the group with which they are associated, each sender including a plurality of registers, means for connecting said senders to the trunks of the group they 25 normally serve, means for connecting the senders of a given group to the trunks of groups other than the one they normally serve, means controlled over said trunks for variably setting the registers of said senders, and means controlled by said senders according to the setting of the registers for operating the selective switches.
9. In a telephone system, a plurality of groups of trunks, selective switches, a plurality of groups of senders, one associated with each group of trunks, the senders of each group being arranged normally to serve the trunks of the group with which they are associated, each sender including a plurality 30 of registers, means for connecting said senders to the trunks of the groups they normally serve, means for extending a telephone connection over any given trunk in any group, means when all senders of the group normally serving the group of trunks containing said given trunk are busy for connecting an idle sender of some other group to said given trunk, means for sending impulses over said given trunk to set the registers of the connected sender, and means controlled by such sender for operating said selective switches to further extend the telephone connection.
10. In a telephone system, a plurality of groups of trunks, a plurality of senders, one associated with each group of trunks, each of said senders being arranged normally to serve the group of trunks with which it is associated, means including relay contacts for connecting said senders to the trunks of the groups they normally serve, and means including relay contacts for connecting any one of said senders to the trunks of groups other than the group it normally serves.
11. In a telephone system, a plurality of groups of trunks, a plurality of groups of senders, one associated with each group of trunks, the senders of each of said groups being arranged normally to serve the trunks of the group with which they are associated, means including relay contacts for connecting said senders to the trunks of the groups they normally serve, and means including relay contacts for connecting the senders of any group of senders to the trunks of any group of trunks.
12. In a telephone system, a plurality of groups of trunks, a plurality of senders, one associated with each group of trunks, each of said senders being arranged to serve normally the trunks of the group with which it is associated, a group connecting relay individual to each group of trunks, a series of units connecting relays for each sender, each one corresponding to a trunk in the group normally served by such sender, means including contacts of said relays for connecting said senders to the trunks of the groups they normally serve, and means for connecting any sender to the trunks of groups other than the one it normally serves.
13. In a telephone system, a plurality of groups of trunks, a plurality of groups of senders, one associated with each group of trunks, the senders of each group being arranged normally to serve the trunks of the group with which they are associated, a plurality of group connecting relays individual to each group of trunks, there being as many individual relays for each group of trunks as there are groups of trunks, a plurality of series of units connecting relays each relay of each series corresponding to one of the trunks of the groups of trunks, means in-

cluding the contacts of one of the group relays individual to a particular group of trunks and the contacts of said units relays for connecting the senders normally serving 5 said particular group of trunks to the trunks of such group, and means including the contacts of another group relay individual to said particular group of trunks and the

contacts of said units relays for connecting the senders normally serving some other 10 group of trunks to the trunks of said particular group.

In witness whereof, I hereunto subscribe my name this 16th day of June A. D., 1921.

SAMUEL B. WILLIAMS, JR.
